P. J. FORD

GAME.

APPLICATION FILED OCT. 29, 1920.

Patented May 17, 1921.

FIG. 1.

Patrick J. Ford

INVENTOR.

UNITED STATES PATENT OFFICE.

PATRICK J. FORD, OF AUGUSTA, GEORGIA.

GAME.

1,378,018.

Specification of Letters Patent. Patented May 17, 1921.

Application filed October 29, 1920. Serial No. 420,508.

To all whom it may concern:

Be it known that I, PATRICK J. FORD, a citizen of the United States, residing at Augusta, in the county of Richmond and State 5 of Georgia, have invented certain new and useful Improvements in Games, of which the following is a specification.

My invention relates to improvements in game apparatus.

10 An important object of the invention is to provide a game apparatus, embodying a game-board and pieces to be played thereon, the starting position of the pieces being dependent upon the date of birth of the player.

15 A further object of the invention is to provide a game apparatus of the above mentioned character, which is interesting to play, and which may be easily played without previous experience.

20 In the accompanying drawings forming a part of this specification, and in which like numerals are employed to designate like parts throughout the same,

Figure 1 is a plan view of a game-board 25 embodying my invention,

Fig. 2 is a similar view of the player pieces.

30 In the drawings, the numeral 5 designates a board, which may be formed of suitably stiff and heavy cardboard or the like, having its upper surface preferably covered in light green, while the invention is in no sense restricted to this color.

35 Elliptical frames 6 are printed or otherwise formed upon the upper surface of the board 5, forming an elliptical space 7, within which are arranged and printed circular spaces 8. The spaces 8 are designated "Days" and are numbered consecutively 40 from 1 to 31, inclusive. The day spaces are preferably red, to be readily distinguished.

45 Within the elliptical frame 6 is an inner frame 9 and outer frames 10. Formed within the outer frames 10 are month spaces 11, which are preferably formed blue. The month spaces 11 are preferably designated 1 to 12, inclusive, consecutively, and are also preferably designated by the name of the month.

50 Within the frame 9 are year spaces 12, which may be white, and numbered, as shown.

In Fig. 2, the numeral 13 designates the

day pieces, 14 the month pieces and 15 the year pieces.

55 In playing the game, from 2 to 10 people may participate. A set of player pieces embodies 31 pieces 13, 12 pieces 14, and 10 pieces 15. A complete set of player pieces is employed for each player, and the sets of 60 player pieces are thoroughly shuffled and dealt to the players, until each has received the same number. Each player writes his name and date of birth upon the graphite section or tablet 16, by means of a suitable 65 pencil. After the date of birth is announced, the superfluous year pieces held by each player may be discarded. Assuming that five players are playing, any one gives the date birth, and that party becomes the 70 dealer of the pieces, and the dealer has the first play, the play continuing around to the left. Assuming that the date of birth announced is February 16, 1919. The dealer plays first and lays down player piece 15 75 marked 1, the player piece 15 marked 9, player piece 15 marked 1 and then player piece 15 marked 9, making 19-19. The year must be completed before the player pieces for the months can be played. If 80 the first player fails to complete the year the next player having the same birth date may complete it, and then pass to the month dates and year dates. Each player playing in turn, lays down as many pieces as he can, 85 consecutively, and the player who first lays down all of the player pieces wins.

85 It is to be understood that the form of my invention herewith shown and described is to be taken as a preferred example of the 90 same, and that various changes in the shape, size, and arrangement of parts may be resorted to without departing from the spirit of my invention, or the scope of the subjoined claims.

95 Having thus described my invention, I claim:

1. A game apparatus of the character described, comprising a board being provided upon its upper surface with day spaces consecutively numbered, month spaces consecutively numbered, and year spaces, in combination with consecutively numbered day pieces, consecutively numbered month pieces and year pieces.

100 2. A game apparatus of the character de-

scribed, comprising a board being provided upon its upper surface with colored day spaces consecutively numbered, month spaces of different color from the day spaces and 5 consecutively numbered, and year spaces of different color than the day and month spaces, in combination with day pieces consecutively numbered and having the same color as the day spaces, month pieces con-

secutively numbered and having the same 10 color as the month spaces, and year pieces having the same color as the year spaces.

In testimony whereof, I have affixed my signature in the presence of two witnesses.

PATRICK J. FORD.
